UNITED STATES PATENT OFFICE

2,100,240

CONTAINER

Julius N. Cayo, Benton Harbor, Mich.

Application April 23, 1936, Serial No. 75,986

1 Claim. (Cl. 229—5.5)

This invention relates to the cylindrical container for the packaging and mailing of merchandise or the like and the method of manufacturing the same.

5 The objects of the invention are:

First, to provide a container of combined paper and metal which is substantially sealed, which is very strong and simple, and produced without the use of rivets or other similar attaching devices.

10 Second, to produce such a structure in which the crimping of the paper wall upon the metal will serve as an effective fastening means for the end closures of such a receptacle.

15 Third, to provide an improved process and means for the manufacture of such a container.

Further objects pertaining to details will appear from the description to follow. I accomplish the objects of my invention by the devices and means illustrated in the accompanying drawing, in which:

Fig. 1 is a longitudinal axial section through a cylindrical container embodying my invention.

20 Fig. 2 is a detail view of the method of producing the cylindrical wall of the container.

Fig. 3 is a detail vertical sectional view of the machine or apparatus for crimping the ends of the cylinder walls onto the metallic heads or ends of the container.

25 Fig. 4 is an inverted plan view looking at the face of the crimping head.

Fig. 5 is an enlarged detail sectional view on line 5—5 of Fig. 4, showing the detail of the bottom of the groove.

30 Fig. 6 is an enlarged sectional detail showing the method of action of the spinning crimper head in crimping ends of the container bottom.

The parts will be identified by their numerals of reference which are the same in all the views.

35 Fig. 1 is the cylindrical body of the container. 2 are the sheet metal heads therefor of stamping with out-turned flanges 3. The walls of the body

40 are made up of a central portion 4 of spirally wound cheap paper tube, preferably made of

45 quite heavy material and cut off square at the ends to form the shoulders for receiving the heads 2 of the container. An outer layer 5 is

50 made up by wrapping a firm high quality of paper, kraft or otherwise, around the tube as seen in Fig. 2, forming the shoulders 6 against which the metallic heads 2 rest. This makes the outer covering of the wall of one or more plies of paper. After the container has been filled or

the article desired to be shipped in it has been

introduced, it is closed by inserting the head 2 against the shoulder 6 and subjecting the projecting edge of the outer layer 5 to the action of a crimping machine which is made up preferably of a head containing concentric grooves successively of the diameter to correspond to the particular package to be closed.

5 This is seen in a preferred form in Fig. 3 in which the spinning head 7 is driven by an electric motor 8 being directly mounted on the arbor 10 thereof. The whole machine is supported on a suitable base 10 with a standard 11 flanged at 12 to receive the motor 8. The head 7 is provided with concentric grooves 13 in the bottom of each groove, there being a projection 14 which spreads out the laminated layer 5 and crimps it over the flanged edge 3 of the metallic head 2. In the preferred form this head 2 is supported by the shoulder 6.

10 I provide a table 15 on rack plunger 16 operated by pinion and crank. The packages should be held by the hand in this operation. Only one groove is needed for each size.

15 The revolving plate may be provided with a crank for its operation and the package may be held in the hand against the revolving plate without other support and do an effective job of crimping.

20 I have specified sheet metal heads for the structure. This, however, is the preferred form, 30 as an equivalent of the metal head might be made by spinning or stamping the same firmly from fiber. The head might be formed of sheet celluloid with which, of course, it could be made transparent and the head could be formed in a 35 variety of ways with the flange in position to receive the crimped edge. I desire to claim the same as metallic and also to claim the same broadly.

Having thus described my invention, what I 40 claim as new and desire to secure by Letters Patent is:

45 A mailing tube or package comprising an inner body of spirally wound low grade paper tube, an outer layer of kraft paper wrapped thereon in concentric layers and projecting beyond the end of the spiral tube to form shoulders, and flanged heads for said container bottomed against the ends of the inner tube with the projecting ends of the kraft paper layer bent 50 and crimped over the flanges of the heads, whereby the heads are retained in place by the folding and crimping of the kraft paper.

JULIUS N. CAYO.
